Inventor, E. Page

United States Patent Office.

ENOS PAGE, OF STREETSBORO, OHIO.

Letters Patent No. 79,383, dated June 30, 1868.

IMPROVEMENT IN SHEEP-TABLE, &c.

The Schedule referred to in these Letters Patent and making part of the same.

TO ALL WHOM IT MAY CONCERN:

Be it known that I, ENOS PAGE, of Streetsboro, in the county of Portage, and State of Ohio, have invented certain new and useful Improvements in Sheep-Tables, &c.; and I do hereby declare that the following is a full and complete description of the same, reference being had to the accompanying drawings, making a part of this specification, in which—

Figure 1 is a side view of the table.

Figure 2, a view of the under side.

Figure 3, a view of the top.

Like letters of reference refer to like parts in the several views.

In fig. 3, A represents the top of the table, to the under side of which are hinged the legs B, fig. 2, by means of the hinges or butts C, one wing of which is secured to the table-top, and the other to the cross-piece D, in which the legs are inserted, so that the two legs can be folded or turned up at once, close to the under side of the top, as are the legs E, which, as will be observed, are not connected to each other and to the top by a cross-piece, but are directly hinged to the table by the butts, indicated by the dotted lines *a*.

The legs B on being turned down, as represented in fig. 1, are thus secured by the button F, thereby dispensing with the use of braces for sustaining the legs in position; a transverse brace, G, only being required.

The legs E referred to, when turned down, as are the legs B, are secured from rocking by their upper end being embraced in the recesses H cut in the cross-piece I, and which is therein stayed by the buttons I', said buttons being turned down over the legs, as shown in fig. 1.

J is a pillow, fixed to the top of the table, in which is a deep rounded notch for the admission of the neck of the sheep on being laid upon the table for shearing, and to which it is secured by a strap passed over its neck or body, as may be most convenient.

The special advantage of a table thus constructed, viz, with the legs so attached that they can be folded up, is the great convenience of transportation and storage. The ordinary shearing-table with its rigid legs is cumbersome for moving, and occupies much room when placed away for safe keeping; whereas, the table above described, by having its legs folded up, can be easily moved about, or set up close against the wall out of the way.

What I claim as my invention, and desire to secure by Letters Patent, is—

Hinging the legs B and E to the table or top A, in the manner as and for the purpose set forth.

ENOS PAGE.
